(57) **CLAIM**

The ornamental design for a fish body position fixation plate, as shown and described.

DESCRIPTION

Figure 1.1 shows a back view of a fish body position fixation plate according to my new design;

Figure 1.2 shows a front view of a fish body position fixation plate according to my new design;

Figure 1.3 shows a right view of a fish body position fixation plate according to my new design;

Figure 1.4 shows a left view of a fish body position fixation plate according to my new design;

Figure 1.5 shows a back view of a fish body position fixation plate according to my new design;

Figure 1.6 shows a bottom view of a fish body position fixation plate according to my new design; and

Figure 1.7 shows a perspective view of a fish body position fixation plate according to my new design.
